US00D515897S

(12) **United States Design Patent** (10) Patent No.: **US D515,897 S**
(45) Date of Patent: **** Feb. 28, 2006**

(54) **TRACTOR TOOL HOLDER**

(75) Inventor: **Michael Greene**, Reno, NV (US)

(73) Assignee: **Thinking Outside, L.L.C.**, Detroit, MI
(US)

(**) Term: **14 Years**

(21) Appl. No.: **29/189,992**

(22) Filed: **Sep. 11, 2003**

(51) LOC (8) Cl. **08-05**

(52) U.S. Cl. **D8/71**

(58) Field of Classification Search **D8/71, D8/14, 70, 72, 73, 74, 349, 354, 373, 395; D15/28, 130, 132, 138, 139, 140, 141; 173/132; 206/349; 211/70.1, 70.6; 248/127, 146, 156; D6/553; 224/410**

See application file for complete search history.

(57) **CLAIM**

The ornamental design for tractor tool holder, as shown and described.

DESCRIPTION

FIG. 1 is a perspective view of a tractor tool holder showing my new design; and,

FIG. 2 is another perspective view thereof.

Phantom lining, where utilized, is for illustrative purposes only, is not intended to limit the claimed component design to the features shown in phantom, and forms no part of the claimed design.

1 Claim, 2 Drawing Sheets

FIG. 1
